OTHER PUBLICATIONS

U.S. Appl. No. 29/261,348, Coushaine et al., Light Emitting Diode Bulb Connector, filed Jun. 13, 2006.

Primary Examiner—Daniel D Bui
Assistant Examiner—Thomas J Johannes

(74) *Attorney, Agent, or Firm*—Sterne, Kessler, Goldstein & Fox P.L.C.

(57) **CLAIM**

The ornamental design for a light emitting diode bulb connector, as shown and described.

DESCRIPTION

FIG. 1 is a top perspective view of a light emitting diode bulb connector showing our new design; and,

FIG. 2 is a bottom perspective view thereof.

1 Claim, 1 Drawing Sheet
